WEDGE TYPE BOLT OR PIN

John V. Hammond, Spangler, Pa.

Application June 25, 1951, Serial No. 233,447

1 Claim. (Cl. 85—6)

1

This invention relates to a wedge type bolt or pin and, more particularly to such a bolt for use in mining.

A primary object of the invention is the provision of a bolt or pin which may be inserted in a hole in the roof of a coal mine or the like for holding up rock or slate or other material having laminated strata.

An additional object of the invention is the provision of such a pin which, when inserted in the roof, will expand the full length of its associated bore to completely fill the same thus precluding the entrance of air into the hole to loose the rock or slate of the roof.

A further object of the invention is the provision of such a pin which will serve to tie various laminations or layers of slate together to preclude the falling of the lowermost layer.

Still other objects reside in the combinations of elements, arrangements of parts, and features of construction, all as will be more fully pointed out hereinafter, and shown in the accompanying drawing wherein there is disclosed a preferred embodiment of the inventive concept.

In the drawing:

Figure 1 is a fragmentary diagrammatic sectional view of a mine roof showing the bolt of the instant invention in position.

Figure 2 is an elevational view of the bolt.

Figure 3 is a sectional view taken substantially along the line 3—3 of Figure 2 as viewed in the direction indicated by the arrows.

Figure 4 is a sectional view taken substantially along the line 4—4 of Figure 2 as viewed in the direction indicated by the arrows.

Figure 5 is a sectional view taken substantially along the line 5—5 of Figure 2 as viewed in the direction indicated by the arrows.

Referring now to the drawings in detail, there is generally indicated at 10 the roof of a coal mine or the like comprised of layers or strata 11 of rock, slate, or similar material, and supported in the customary manner by spaced shoring 12. In the event that loose rock is located between shoring at a point such as 13 a bore 14 is drilled through the lower strata into one or more succeeding strata, and the pin generally indicated at 15 of the instant invention driven thereinto, as will be more fully explained hereinafter.

Referring now to the pin in detail it is comprised of a cylindrical member 16 preferably comprised of wood or similar material of any desired useful length depending on the conditions of the particular mine in which it is adapted to be used. The member 15 is provided with two V-

2

shaped grooves 17, the grooves being widest at opposite ends of the pin. Grooves 17 taper gradually to intersecting points, as best shown in Figures 3 and 5 which points are positioned at right angles to each other, each groove extending slightly past the center line of member 16. A wedge 18 of a taper conforming to the taper of each groove 17 is adapted to be inserted in each groove extending from opposite ends of member 16. Each wedge is provided at its apex with a centrally positioned V-shaped slot, whereby the wedges when driven inwardly to their fullest extent may intersect at the apexes of the V-shaped grooves.

15 The use and operation of the device should now be readily understandable. The hole or bore 14 is first drilled to a depth slightly less than the length of the pin 15. The wedges 17 are then inserted in their oppositely positioned grooves 10 and the pin, which is of a diameter very slightly less than that of the bore, is inserted to its fullest extent therein, until the end of the uppermost wedge 18 abuts the top 20 of bore 14. Further driving, as by means of a sledge against the exposed end of the lower wedge will cause the wedges 18 to enter grooves 17 to their fullest extent, thus expanding the member 16 completely to fill bore 14 throughout the entire length thereof to preclude the entrance of air into the bore and, consequently, into any cracks between the laminations or strata of the rock or slate, thus effectively preventing the fall of the material of the roof.

Due to the fact that the opposite ends of the V-shaped groove 17 will be expanded slightly more than the central portion of bolt 15, it will also be apparent that the member serves effectively to pin the lowermost strata of the mine roof to adjacent strata.

30 40 It will be readily understandable that the pin of the instant invention is not intended to be utilized as a substitute for shoring within a mine, but is utilized in such places between the shoring as indicate the presence of loose rock or similar material.

45 As many embodiments may be made of this inventive concept and as many modifications may be made in the embodiment herein shown and described, it is to be understood that all matter herein is to be interpreted merely as illustrative and not in a limiting sense.

What is claimed is:

A wedge type bolt for mines, comprising a cylindrical member having a V-shaped groove in each end of said member and a wedge in each

groove, said wedges being of substantially the configuration of said grooves and when fully inserted extending beyond the ends of said member, the total length of said wedges being greater than the length of said member, said grooves being at right angles to each other and intersecting at the mid point of said cylindrical member, each said wedges being provided with a centrally positioned V-shaped groove at its apex whereby when fully inserted they may intersect, the sides of said wedges being arcuate and having a radius of curvature conforming to that of said cylindrical member, driving of said wedges in the grooves of said member effecting expansion of said member substantially throughout the length thereof.

JOHN V. HAMMOND.
